213,320

REMOTE CONTROL UNIT FOR A MOTION PICTURE PROJECTOR

Dianne B. Ainslie, 22 Bobrich Drive,
Rochester, N.Y. 14610

Filed Feb. 5, 1968, Ser. No. 10,440

Term of patent 14 years

U.S. Cl. D26—13

Int. Cl. D14—01

FIG. 2

FIG. 4

FIG. 1

FIG. 5

FIG. 3

FIG. 6

FIG. 1 is a top plan view of a remote control unit for a motion picture projector;

FIG. 2 is a front elevational view of the remote control unit;

FIG. 3 is a rear elevational view of the remote control unit;

FIG. 4 is a side elevational view of the remote control unit;

FIG. 5 is a side elevational view of the remote control unit showing the side opposite to that shown in FIG. 4; and

FIG. 6 is a bottom view of the remote control unit.

I claim:

The ornamental design for a remote control unit for a motion picture projector, as shown.

UNITED STATES PATENT OFFICE
CERTIFICATE OF CORRECTION

Design No. 213,320

February 18, 1969

Dianne B. Ainslie

It is certified that error appears in the above identified patent and that said Letters Patent are hereby corrected as shown below:

In the grant, line 3, after "New York," insert -- assignor to Eastman Kodak Company, of Rochester, New York, a corporation of New Jersey, --; line 13, "Dianne B. Ainslie, her heirs" should read -- Eastman Kodak Company, its successors --. In the heading to the drawings and printed specification, lines 4 and 5, "22 Bobrich Drive, Rochester, N. Y. 14610" should read -- Rochester, N. Y., assignor to Eastman Kodak Company, Rochester, N. Y., a corporation of New Jersey --.

Signed and sealed this 24th day of March 1970.
